UNITED STATES PATENT OFFICE

2,595,660

DISHWASHER OR THE LIKE

Charles Hollerith, Jackson, Mich., assignor to
Lake State Products, Inc., Jackson, Mich., a
corporation of Michigan

Application December 29, 1945, Serial No. 638,317

1 Claim. (Cl. 134—186)

1

The present invention relates to improvements in dishwasher construction and pertains to the same type construction shown in my co-pending application, Serial No. 638,316, filed on December 29, 1945.

An object of the invention is to provide an impeller, drain valve and electric motor unit for dishwashers and the like, involving a minimum of structural parts.

Another object is to provide a unit of the described type, in which the valve is opened by the action of gravity and closed by the operation of the electric motor actuating the impeller.

A further object is to provide a drain valve and impeller unit which is raised to close the valve and dropped by gravity to open the valve when the electric motor circuit is closed.

A still further object of the invention is to provide a drain valve and impeller unit for dishwashers and the like, in which an electric motor is provided, having an axially floated armature including a drive shaft carrying the impeller as well as the drain valve, in which the armature is so located relative to the magnetic field that the drain valve is magnetically actuated in one direction and is actuated by gravity in the opposite direction.

These and other objects and advantages presented will be more fully appreciated upon consideration of the following specification and claim.

In the drawings,

Fig. 1 is a vertical section through the unit, and

Fig. 2 is a fragmentary plan view of the clamping band for supporting the unit from the vat.

Referring to the drawings, the vat 10 has an opening 12 closed by a sump 14, to which the motor housing 16 is attached by bolts 18. A gasket and seat 20 is clamped between the flanges 22 and 24 by an adjustable, sectional sheet metal band 26. As more clearly shown in Fig. 2, the band 26 comprises sections 28 and 30 having a hook-and-eye connection 32 and flanges at 34 to receive adjustable bolts 36. Through this arrangement, the joint between the vat 10 and sump 14 is sealed at the same time the parts are firmly assembled together.

Armature 38 of the electric motor 40 has a shaft 42 having a slip fit at 44 and a bearing 46, and a slip fit at 48 and a bearing 50. The packing gland 52 also serves as a further bearing for the upper end of the shaft 42. The reduced portion 54 of the shaft 42 provides a shoulder 56 to support the lower raceway of the bearing 50 while the upper raceway is driven by the central tubular portion 60 of the drain valve 62. The impeller 64 is attached to the upper end of

2

the shaft 42 by a screw 66 clamping the impeller 64 against the spacer 68.

When the motor circuit is closed, the magnetic field created by the winding 70 will tend to lift the armature 38 upwardly to the field. This will result in the valve 62 engaging with the seat 71 of the gasket 20 to close the drain opening in the vat 10. When the motor circuit is opened, the valve and impeller unit will drop by gravity into the position shown in the drawing. It will be obvious that the arrangement between the bearing 50 and its associated parts enables the valve 62 to remain stationary while the impeller 64 and shaft 42 are rotating at engine speed.

As a further refinement of the construction, it will be noted that the impeller 64 has a conical recess 72. Thus shaped, the liquid is thrown out of the recess 72 and away from the bearing 50 and its associated structure.

Having thus described my invention, what I claim as new and desire to be protected by Letters Patent is:

In a dishwasher and the like, a valve and impeller unit comprising a sump, a motor having stator windings and a rotor mounted beneath said sump, a vertical drive shaft connected to and driven by said rotor and extending from said motor through said sump to a point above said sump, an impeller mounted on the upper end of said shaft, a drain valve surrounding said shaft and having a connection with said shaft, a seat defining an opening surrounding said shaft and located above said drain valve at its outer periphery, said rotor with said windings de-energized being located axially to one side of the magnetic field of said windings whereby upon energizing said windings said rotor and shaft are lifted to bring said rotor into the magnetic field of said windings to close said valve, said valve and shaft being free to drop by gravity to open said valve and return said rotor to its offset position.
